UNITED STATES PATENT OFFICE.

FRED S. CARR, OF NEWTON, MASSACHUSETTS, ASSIGNOR TO CARR FASTENER COMPANY OF CAMBRIDGE, MASSACHUSETTS, A CORPORATION OF MAINE.

FASTENER.

Application filed June 14, 1924. Serial No. 719,919.

This invention aims to provide an improved stud and socket fastener of the push-button type.

In the drawings, which illustrate a preferred embodiment of my invention:—

Figure 1 is a front elevation of the preferred form of fastener;

Fig. 2 is a rear elevation of the stud attached to a curtain;

Fig. 3 is a section, partly in elevation, on the line 3—3 of Fig. 1, showing the stud slightly entered within the socket;

Fig. 4 is a section similar to Fig. 3, showing the stud entered further into the socket;

Fig. 5 is a section similar to Fig. 3, showing the stud locked within the socket;

Fig. 6 is a section on the line 6—6 of Fig. 5; and

Fig. 7 is a front elevation of the socket attached to the body of an automobile.

Referring to the drawings, I have shown a stud attached to a curtain 9 by means of prongs 11 projecting from a front plate 13 and engaging a back plate 15 substantially as more fully illustrated and described in the co-pending application filed herewith, Serial No. 719,917.

The preferred form of stud, as illustrated, presents a socket-engaging member 17 pressed from a base 18 and provided with slots 19 to permit contraction and expansion of the socket-engaging member when engaging or disengaging a socket. This member is preferably secured to the front plate 13 substantially as illustrated and described in the above-mentioned application.

While the socket-engaging member 17 may be secured to a socket and held in engagement therewith by its own resiliency, I prefer to provide locking means 23 for locking the socket-engaging member against contraction when engaged with a socket.

The locking means 23 comprises a press-button 24 presented at the face of the front plate 13 and a locking head 25 normally extending beyond the socket-engaging end of the socket-engaging member 17. The locking means is held in normal position by a spring 27 interposed between a flange 28, located upon the locking means, and the front plate 13.

The flange 28 also limits the forward movement of the locking means by engagement with the shoulder or adjacent the neck 55 of the socket-engaging member 17.

The preferred form of socket includes a casing 29 secured to the sheet metal side 30 of an automobile by a plurality of prongs substantially as shown and described in the above-mentioned co-pending application. 60 This casing presents a stud-receiving aperture normally closed by a sealing disc 31, which is urged into aperture-closing position by a spring 33 substantially stronger than the spring 27 located in the stud.

The stud may be engaged with the socket by pressing upon the front plate 13 thereby urging the stud toward the aperture in the socket. Because the locking head 25 is normally beyond the reversely bent portion 35 of the socket-engaging member 17, the head of the socket-engaging part may contract and enter the aperture in the socket without interference from the locking head, as best illustrated in Fig. 3. The sealing disc 31 75 is provided with a depression so that the locking head 25 may pass through the stud-receiving aperture and into the depression without engaging the sealing disc during initial contraction of the head of the stud. 80 Thus, when the stud is moved into full engagement with the socket, the locking head is excluded from engagement with the reversely bent portions 35, and the locking head 25 engages the sealing disc 31 and 85 forces it inwardly against the pressure of the spring (Fig. 4) until the head of the stud has passed through the stud-receiving aperture and again expanded to its normal position. The strong spring 33 then urges 90 the locking head 25 into engagement with the reversely bent portions 35 against the pressure of the weaker spring 27, thereby locking the stud and socket together and preventing accidental separation thereof, as 95 best illustrated in Fig. 5.

Separation of the stud from the socket may be effected by grasping the lower edge of the curtain and exerting a slight outward pull thereon, at the same time pressing the 100 press-button to displace the locking head 25 from engagement with the reversely bent portions 35 of the socket-engaging member 17.

While I have shown and described a preferred form of one embodiment of my invention, it will be understood that changes involving omission, substitution, alteration and reversal of parts, and even changes in the mode of operation, may be made without 105 110

departing from the scope of my invention, which is best defined in the following claims.

Claims:

1. A stud and socket fastener comprising, in combination, a socket presenting a stud-receiving aperture, a cooperating stud having a socket-engaging member contractible and expansible for engagement in said aperture, a locking member forming part of the stud assembly, spring means also forming part of the stud assembly for normally holding said locking member in unlocked position to permit engagement of the stud and socket while said locking member is held in said unlocked position and spring means forming part of the socket assembly for axially moving said locking member into engagement with said socket-engaging member when engaged in said stud-receiving aperture thereby to prevent separation of the stud and socket.
2. A stud and socket fastener comprising, in combination, a socket presenting a stud-receiving aperture, a cooperating stud having a socket-engaging member contractible and expansible for engagement with said aperture, a spring-pressed locking member forming part of the fastener assembly and normally out of engagement with said socket-engaging member when the stud and socket are disengaged and means for axially moving said locking member into engagement with said socket-engaging member when engaged in said stud-receiving aperture, thereby to prevent separation of said stud and socket, and a press-button also forming part of the fastener assembly, said press-button being shiftable to move said locking member into unlocking position to permit separation of said stud and socket.
3. A stud and socket fastener comprising, in combination, a socket presenting a stud-receiving aperture, a spring-pressed sealing disc carried by the socket and normally closing said aperture, a cooperating stud presenting a contractible and expansible socket-engaging member, a spring-pressed locking member carried by the stud member and normally extending beyond the free end of said socket-engaging member, said locking member operatively urged into engagement with said socket-engaging member by said spring-pressed sealing disc when said stud and socket are engaged, and a press-button carried by the stud for operatively moving said locking member out of engagement with said socket-engaging member.
4. A stud and socket fastener comprising, in combination, a socket presenting a stud-receiving aperture, a stud including a head, a neck and shank portion contractible and expansible for engagement with said aperture, reversely bent portions located at the head of said stud, a press button member carried by said stud and presenting a locking

head for locking said stud and socket together and a spring having one end seated against said press button member for normally urging said locking head beyond the free end of said stud head to permit contraction of said head when engaging the wall of said aperture without manipulation of said press button member the other end of the spring being seated against a portion of the stud.

5. A stud and socket fastener comprising, in combination, a socket having a stud-receiving aperture, a sealing disc carried by the socket and normally closing said aperture and a substantially stiff spring also assembled with the socket for holding said sealing disc in closed position, a stud having a contractible and expansible head for engagement with said aperture and a locking member normally urged into unlocked position by a substantially weak spring, said locking member and weak spring being assembled with the stud, said first-mentioned spring acting upon said locking part to overcome the pressure of said weak spring thereby to force said locking part into locking position when said head is engaged in said aperture.

6. A stud and socket fastener comprising, in combination a socket having a stud-receiving aperture, a sealing disc carried by the socket and normally closing said aperture and a substantially stiff spring also assembled with the socket for holding said sealing disc in closed position, a stud having a contractible and expansible head for engagement with said aperture and a locking member normally urged into unlocked position by a substantially weak spring and a press-button integral with said locking member, said locking member, press-button and weak spring being assembled with the stud, said first-mentioned spring acting upon said locking part to overcome the pressure of said weak spring thereby to force said locking part into locking position when said head is engaged in said aperture, said press-button manually operable to displace said locking member, thereby permitting contraction of said head and separation thereof from said socket.

7. A stud for a press-button fastener including a contractible and expansible socket-engaging head, a locking member, and a spring normally holding said locking member in a position beyond the free end of and out of engagement with said head so as to permit free contraction of said head when presented for engagement with a socket, said locking member and spring forming part of the stud assembly.

8. A stud for a press-button fastener including a contractible and expansible socket-engaging head, a locking member normally extending beyond the socket-engaging end of

said head to permit contraction of said head for engagement with a socket, a spring pressing said locking member into its normal position, and a press-button capable of being moved by pressure only when said stud is locked with a suitable socket, said locking member, spring and press-button forming a part of the stud assembly.

9. A stud and socket fastener comprising, in combination, a stud presenting a contractible and expansible socket-engaging portion, spring-pressed means assembled with said stud for reciprocal movement relative thereto, said means presenting a locking part normally held in unlocked position by the spring to permit free contraction of the socket-engaging portion when being engaged with a socket, a cooperating socket presenting a stud-receiving aperture for reception 20 of said socket-engaging portion and means

carried by said socket for automatically pressing said locking part into locking engagement with said socket-engaging part when engaged in the stud-receiving aperture.

10. A stud and socket fastener comprising, in combination, a socket member presenting a stud-receiving aperture, a cooperating stud member having a socket-engaging part for engagement in said stud-engaging aperture, a locking member and spring element assembled with one of the fastener parts, said spring element normally holding said locking member in unlocked position, and spring means forming part of the other fastener member for pressing said locking member into locking position when the fastener parts are engaged.

In testimony whereof, I have signed my name to this specification.

FRED S. CARR.
